UNITED STATES PATENT OFFICE.

PIERRE GILLES, OF SPRINGFIELD, MASSACHUSETTS.

CARBURETER.

1,183,294.

Specification of Letters Patent. Patented May 16, 1916.

Application filed February 17, 1915. Serial No. 8,723.

To all whom it may concern:

Be it known that I, PIERRE GILLES, a subject of the Emperor of Germany, residing in the city of Springfield, county of Hampden, and State of Massachusetts, have invented certain new and useful Improvements in Carbureters, of which the following is a specification.

This invention relates to improvement in carbureters and particularly to carbureters of the compensatory type, wherein an auxiliary nozzle fed with fuel at a uniform rate is provided in connection with the usual suction feed nozzle.

I am aware that the compensatory type of carbureter is not broadly new and that it is disclosed in various forms in the prior art. These carbureters operate upon the principle that an auxiliary nozzle, which has a constant supply per unit of time, will coöperate with the usual nozzle, which depends wholly for its feed on the suction, to produce a mixture having a constant ratio of air to fuel at all engine speeds. Carbureters of this type have been successfully and widely used but, although theoretically the constant ratio of air to fuel is obtained, as a practical matter the theoretical conditions are not always obtained. It is desirable, therefore, to provide means whereby the supply to each nozzle may be varied independently of the other so that the desired conditions may be obtained by adjustment. It is also a well-known fact that a carbureter suitable for one car will not operate successfully with another unless adjusted. It is, therefore, desirable to provide, in a standard carbureter adapted to be used on all makes of cars, means whereby the necessary adjustments may be conveniently made.

An object of the invention is to provide in a carbureter having suction feed and compensating fuel nozzles, means to vary the flow from the former and independent means to vary the supply to the latter.

Another object is to provide in a carbureter of the compensatory feed type having fuel feed nozzles, and a float controlled supply chamber all within a single casing, a quick detachable cap, whereby the interior of the casing and the devices therein may be exposed for inspection without disturbing the adjusted relation of the devices.

A further object is to provide in a carbureter of the type described, an improved suction nozzle and associated compensating

nozzle structure of extreme simplicity, which involves only two parts and which is characterized, not only by low cost of manufacture but by convenience and rapidity in assembly and removal of parts.

Other objects and advantages will appear in the description to follow and in the annexed claims.

Referring to the drawings:

Figure 1 is a sectional elevation of a carbureter, illustrative of one embodiment of the invention. Fig. 2 is an exterior elevational view of the suction nozzle, shown as removed from the carbureter. Fig. 3 is a detailed view of the means for fastening parts of the carbureter together. Fig. 4 is a top plan view of a modified form of nozzle. Fig. 5 is a sectional plan view taken on the line 5—5 of Fig. 1 and looking in the direction of the arrows. Fig. 6 is a bottom plan view of Fig. 1. Fig. 7 is a detailed sectional view of another modification of the suction nozzle. Fig. 8 is a view similar to Fig. 7, but, illustrating a modified construction of the upper end of the suction nozzle. Fig. 9 is a top plan view of Fig. 8; and Fig. 10 is a top plan view of Fig. 9. Fig. 11 is a sectional elevation of a carbureter showing a preferred modification of the invention; Fig. 12 is a partial sectional elevation showing a modification in the arrangement of the adjusting devices for the nozzles; and Fig. 13 is a fragmentary sectional plan view taken on the line 13—13 of Fig. 11 and looking in the direction of the arrows.

Referring to the drawings in detail and particularly to Fig. 1, 1 designates the main casing of the carbureter and 2 the cover therefor which may be secured by any suitable means to permit ready attachment and detachment when required. A preferred form of attaching means is indicated generally at 3, wherein a threaded bolt 4 is arranged to enter an angular slot 6 best shown in Fig. 3 a nut 7 and a head 5 on the bolt operated to draw the parts together in an obvious manner. The gasoline supply chamber is indicated at 8 and mounted therein is the usual float 9 which actuates the needle valve 10, to open or close the passageway 11. The latter may be connected to a suitable supply by a supply pipe 12. Concentrically arranged within, and with relation to the axis of the casing 1 is a suction pipe 13 which extends entirely therethrough.

Arranged concentrically within the pipe 13 is a vaporizing nozzle 14, the lower end of which is secured to the casing 1 by means of the threads 15 engaging the threaded opening 16. The upper end of the nozzle 14 terminates adjacent the contracted throat 18 of a venturi 19, which is made removable so that other rings may be substituted in order to vary the size of the throat 18 to change the vaporizing effect of the carbureter when required. Located within the vaporizing nozzle 14 is a stem 20 having an axial opening 21 therethrough. The upper end of this opening can be varied by means of a needle valve 22 which is mounted in a threaded opening in the bridge-piece 23 formed integrally with the member 14 as shown in Fig. 2. The upper end 20' of the stem 21 is made slightly smaller in diameter than the internal diameter of the passageway 24, whereby a small annular delivery opening 25 is formed and the lower part of the stem 20 is formed with an enlarged portion 26 which so fits the opening 24 as to form a gasoline tight joint. An orifice 26' in the stem 20 above the portion 26 permits fuel to enter the interior 24 of the nozzle 14. The passageway 21 communicates with a transverse passageway 27 and the latter in turn registers with a passageway 28 which leads, by means of the opening 29 into the float chamber 8. The stem 20 is removably secured within the nozzle 14 by means of the threaded end 17, as shown, and is arranged for convenient removal from the base of the carbureter.

The cover 2 is formed with a passageway therethrough which forms an extension of the pipe 13 and mounted therein is a throttle 31 which is pivotally mounted on a pin 32 whereby the throttle may be operated from the outside by means of a suitable connection in the usual manner. The upper edge of the throttle 31 is formed with a notch 33 which registers with an inlet opening 34. This latter is controlled by a needle valve 35 which is integral with a threaded stem 36, and the valve is retained in its adjusted position by means of a spring actuated pin 37 which engages serrations 38. Leading from the opening 34 is a passageway 39 which communicates with the float chamber 8 below the upper end of the vaporizing nozzle 14.

The object of the passageways 39, 34, and 33 is to permit the motor to be driven at very slow speeds, preferably when the clutch is disconnected, and this is accomplished by closing the throttle 31 to choke off practically all of the flow of the vapors through the throat 18 and confining the flow of gasoline or vapor to the passageways 39, 34, and 33. Stems 20 of different forms may be used within the carbureter nozzle 14, as shown in Figs. 7, 8, 9 and 10.

Referring to Fig. 7, the stem 20 instead of being large enough to fill the opening 24 is formed so that a passageway 40 is left around the enlarged portion 40' of the stem, whereby the gasoline flows through the annular passageway 40, as indicated by the arrows 41, and through the central passageway 21, as indicated by the arrow 42. In this form of nozzle the gasoline, as it issues from the suction nozzle 14 escapes by the 75 annular opening 25 and the small central passage 43.

Referring to Fig. 8; the stem 20 here shown is constructed the same as that described in connection with Fig. 7, except that at the upper end the head portion 44, instead of being made circular, is slabbed off, as indicated at 45 in Figs. 4 and 10. This construction provides delivery openings for the fuel and at the same time the 85 stem 20 is held concentrically within the nozzle 14.

Referring to Figs. 1 and 6, 46 designates a shutter which is pivotally mounted on the lower end of the casing 1 at 47. The handle 48 may be connected by any suitable connections which extend to and within easy reach of the operator. 49 is a spring which normally holds the shutter 46 in the position shown in Fig. 6, whereby a full opening for the passage 13 is provided. During starting operations the shutter 46 may be closed or partly closed and the air drawn in through a tube 50 (see Fig. 5) which may contain warm air, if desired, to facilitate 95 starting in cold weather.

Referring now to the preferred form of carbureter shown in Fig. 11, 50' designates a removable tube which closely fits an axial hole in the casing 1. Within this tubular member is a stem 52' which has an axial passageway 52' therethrough. The upper end 53' of the stem 52' is formed like that shown in Fig. 8 at 44, so that delivery openings are provided for the tube 50'. 54' designates an enlarged portion near the lower end of the stem 52' which has a gasoline tight fit with the tubular member 50. The stem 52' is secured in the casing 1 by a threaded lower portion 51' and may be removed together with the tube 50' when desired by the squared lower end. 55 is an annular groove cut into the casing 1 outside the tube 50' to permit the gasoline to readily flow to an aperture 56 which is controlled 105 by means of a needle valve 57 whereby gasoline may flow from the reservoir 58 through the openings 59 and 56 to the interior of tube 50'. It will also be seen that gasoline 110 can be drawn into the suction pipe 60 through the passage 52' which is connected as shown to the float chamber by the openings 59 and 59'. 61 is a needle valve which 115 controls the flow of gasoline from the passage 52'. It is also to be noted that the 120

valve 61 is readily accessible by removing the cap 2 as is also the float chamber. Throttles 62 and 63 are located within the main passageway 60, as shown, and may be controlled by suitable lever connections.

Fig. 12 shows a tubular member 64 integral with the casing 1 which is the equivalent of the tube 50' just described. An inner stem 65 is similar in construction with that shown at 20 in Fig. 1, except the inner bore 66 is made larger in order to receive a needle valve 67 which can be adjusted by means of a thread 68 and nut 69, to control the outlet opening 70. The gasoline supply is indicated at 71 and flows therefrom through the opening 72 to the passageway 73 from which it enters the bored out portion 66 of the stem 65. 74 is a needle valve, similar to that already described, to control the opening 75 whereby the supply of gasoline to the tubular member 64 may be varied.

In operation, fuel is delivered from the main centrally disposed nozzle by a direct suction from the float chamber. Accordingly, as the engine runs faster the suction from the main nozzle is increased and with slow engine speeds less fuel is delivered. With the main nozzle alone, it has been found that the ratio of fuel to air varies from a minimum at low speeds to a maximum at high speeds. In practice, it is desired to maintain this ratio constant for all speeds, and the auxiliary nozzle is designed to work in a compensatory manner with the main nozzle. The fuel feed to the auxiliary nozzle is substantially uniform per unit of time. Consequently, when the engine runs slow, more fuel is in the auxiliary nozzle, available to be drawn out by suction to compensate for the decreased feed from the main nozzle, than when the engine is running at higher speeds. In the latter instance, the amount of fuel from the main nozzle is increased and that from the auxiliary nozzle is decreased. The use of these two nozzles theoretically results in a constant ratio of air to fuel at all engine speeds. In practice, however, the desired result is not always obtained, and it is, therefore, possible to vary the amount of fuel from either nozzle to obtain the theoretical conditions by the use of the needle valves described. The latter also permit a standard carburetor to be provided for all cars, wherein the necessary adjustments may be made to adapt the carburetor to the peculiar conditions of each particular make of car.

What I claim is:

1. A carburetor, comprising, in combination, a casing formed with a fuel supply chamber and a suction conduit extending centrally through said chamber, a tubular member mounted in said casing, and extending within said conduit, the axes of said

tube and conduit being in rectangular relation, a main nozzle removably secured in the tubular member in concentrical relation thereto to form an annular passage between the nozzle and said member, an axial fuel passage formed in said nozzle, an integral head portion formed on said nozzle at the top of said tubular member and constructed to form a delivery opening between the head and the member, whereby an auxiliary nozzle is formed, a transverse fuel passage communicating with the nozzle at the base of said axial passage, a connection from said chamber to the transverse passage, said nozzle having an integral enlarged portion to closely fit the base of said tubular member, an orifice in the latter and a connection from said chamber to said orifice, all constructed and arranged to form a compact structure with a minimum of parts.

2. A carburetor, comprising, in combination, a casing formed with a fuel supply chamber and an integral suction pipe extending horizontally through said chamber, a tubular member mounted in said casing and extending within said suction pipe, a nozzle removably secured within said member in concentrical relation therewith, an axial fuel passage formed in said nozzle, a transverse fuel passage communicating with the nozzle at the base of said axial passage, a connection from said chamber to said transverse passage, said nozzle having an integral enlarged portion to closely fit the base of said tubular member and an integral head portion positioned at the top of said tubular member and constructed to form a delivery opening between the head and the member, whereby an auxiliary nozzle is formed, and a passage formed in the casing communicating with said chamber and the annular space between said nozzle and member, all constructed and arranged so that a double nozzle is formed with a two piece structure.

3. A carburetor, comprising in combination, a casing, formed with a substantially cylindrical fuel supply chamber open at its upper end and a suction conduit extending entirely through said chamber in rectangular relation to the axis of the latter, said conduit being open to the air at one end and at the other being provided with flanges integral with the casing for close attachment to the intake manifold of an engine, a tube mounted in the lower part of the casing in concentric relation with the axis thereof and extending upwardly within said conduit, a main nozzle within said tube and removable from the base thereof, said nozzle having an integral enlarged portion arranged to close all entrance from below to the annular space between the nozzle and tube, connections between the nozzle and said chamber, connections between the latter and said annular

space above said enlarged portion, a needle valve depending through the suction conduit to control the amount of fuel issuing from said nozzle, and a quickly detachable cap for the upper end of said casing, all constructed and arranged to permit the carbureter to be attached in close proximity to the intake manifold and to permit convenient accessibility for inspection and repair.

10 4. A carbureter, comprising a single casting formed with a fuel supply chamber and a suction conduit extending through said chamber, the axes of the conduit and chamber being in rectangular relation, a tubular nozzle member mounted in said casting in concentrical relation with the axis of said chamber and extending within said conduit, an orifice formed in said member, connections formed in said casting between said orifice and said chamber, a main nozzle removably secured within said tubular member in concentrical relation thereto and arranged to leave an annular space between the tubular nozzle member and said main nozzle, an axial fuel passage formed in the latter, an integral enlarged portion on the main nozzle constructed to closely fit the base of the tubular nozzle member, a connection formed in the casting to communicate between said chamber and the base of said axial passage, and an integral head portion formed on the main nozzle at the top of the tubular member constructed to form

a delivery opening between the head and the tubular member.

5. The combination in a carbureter of the compensatory fuel feed type, a casing formed with a fuel supply chamber, a tubular member secured in said casing, a main nozzle removably secured in the tubular member and extending within said member in concentrical relation thereto, an axial fuel passage formed in said nozzle, a transverse fuel passage communicating with the nozzle at the base of said axial passage, a connection from the chamber to said transverse passage, said nozzle having an integral enlarged portion to closely fit the base of said tubular member, and an opening in said tubular member above said enlarged portion, whereby fuel may be delivered at a uniform rate to the tubular member, said nozzle having an integral head portion at the top of said tubular member constructed to form a delivery opening between the head and the member, whereby an auxiliary nozzle is formed to deliver fuel in compensatory relation to the main nozzle, all constructed and arranged so that a double nozzle of the compensatory type is formed with a two piece structure.

PIERRE GILLES.
